(57) **CLAIM**

The ornamental design for a shade element for a sensor, as shown and described.

DESCRIPTION

FIG. 1 is a perspective view of a shade element for a sensor; FIG. 2 is a front view of the shade element of FIG. 1; FIG. 3 is a back view of the shade element of FIG. 1; FIG. 4 is a left side view of the shade element of FIG. 1, wherein a right side view is a mirror image of the left side view;

FIG. 5 is a top view of the shade element of FIG. 1; FIG. 6 is a bottom view of the shade element of FIG. 1; FIG. 7 is a second embodiment of FIG. 1 which discloses the shade element and has a black color designation; FIG. 8 is a perspective view of a shade element for a sensor. FIG. 9 is a front view of the shade element of FIG. 8; FIG. 10 is a back view of the shade element of FIG. 8; FIG. 11 is a left side view of the shade element of FIG. 8, wherein a right side view is a mirror image of the left side view;

FIG. 12 is a top view of the shade element of FIG. 8; FIG. 13 is a bottom view of the shade element of FIG. 8; and,

FIG. 14 is a second embodiment of FIG. 9 which discloses the shade element and has a black color designation. The broken lines in the drawings form no part of the claimed design.
